AUTOMATIC STAY FOR LOCK KEEPERS

Filed May 9, 1932

UNITED STATES PATENT OFFICE

JAMES E. PHILLIPS, OF NEW YORK, N. Y.

AUTOMATIC STAY FOR LOCK KEEPERS

Application filed May 9, 1932. Serial No. 610,201.

This invention relates to stays for lock keepers and particularly to an automatic stay which when in use acts as a brace for holding the keeper in place and which may be readily removed any time from a point interiorly of the door.

An object of the invention is to provide a simple strong construction which will brace and reinforce a lock keeper so as to substantially prevent the jimmying thereof.

Another object is to provide an automatic stay for lock keepers wherein there are presented a rod and a permanently fixed member at the keeper and on the floor of the room adjacent the keeper so that the rod may be readily applied and removed at any time, the arrangement being such that the rod is not in the way of the door as it swings open and closed.

An additional object, more specifically, is to provide an automatic stay for lock keepers wherein a bar is used which may be readily swung into position and out of position without the use of tools or other implements.

In the drawing,—

Figure 1 is a sectional view through the doorway of a building showing part of the floor and one of the door jams together with an embodiment of the invention, the lower part of the device embodying the invention being shown in section.

Figure 2 is an enlarged fragmentary view 35 of the lower part of the keeper and the upper part of a stay embodying the invention, some of the lower part being shown in section for illustrating the construction.

Figure 3 is a sectional view through Figure 40 2 on line 3—3, the brace rod being removed.

Figure 4 is a view similar to the upper part of Figure 1 but showing a modified form of the invention.

Figure 5 is a sectional view through Figure 45 4 on line 5—5.

Figure 6 is a view similar to Figure 4 on a reduced scale but showing another form of the invention.

Figure 7 is a sectional view through Figure 50 6 on line 7—7.

Referring to the accompanying drawing by numerals, 1 indicates the floor of a room and 2 one of the door jams, said door jam having a keeper 3 of a well known construction. Associated with the keeper 3 is a 45 socket member 4 adapted to receive the upper end of the stay rod 5. The lower end of said rod 5 is fitted into a socket member 6 secured by screws or otherwise to the floor. This socket member 6 is preferably in line 60 with the edge of jam 2 so that the door may be swung open and closed with rod 5 in place. When the rod 5 is in place, as shown in Figure 1, the keeper 3 is braced so that it cannot be jimmied by reason of the support 65 given thereto by the rod 5 and associated parts. The socket member 4 is provided with an upwardly extending flange 7 fitting back of the lower part of the keeper 3 and secured thereto in any desired manner, as, 70 for instance, by screw 8. A pocket 9 is provided in the socket member 4, the same having one wall forming an end abutment 10 for the rod 5. The side walls of the pocket 9 extend forwardly so as to present flanges 75 11 and 12 between which a pivotally mounted latch 13 is mounted. A short groove 14 is provided in flange 12 and a notch 15 is provided in flange 11, whereby a pin 16 may be readily mounted, said pin extending 80 through the latch 13 for pivotally supporting the same. The latch 13 is preferably provided with an enlarged or weighted end 17 so that the latch will normally remain in the position shown in Figure 2 under the 85 action of gravity. When the rod 5 is being swung from the right toward the left, as shown in Figure 2, it will strike the inclined portion 18 and tilt the latch until it moves past the latch into the pocket 9, whereupon the latch will automatically move into the position shown in Figure 2 and prevent 90 accidental removal of the rod 5. When it is desired to remove the rod 5 the hand or one of the fingers presses against the end 19 95 and swings the same downwardly and holds the same in a lowered position until the upper end of rod 5 has been disengaged.

In Figures 4 and 5, the same inventive idea is presented but the embodiment is slight- 100

ly different. In this form of the invention a flange 20 is provided which merges into the rounded abutment 21 and in the shoulder 22 fitting against two of the edges of the plate 23. The lower end of the abutment 21 is provided with a restricted portion 24, whereby an annular shoulder 25 is provided. In this form of the invention, the lower part of the rod 5 is shown in Figure 1, but the upper part is provided with a threaded section 26 on which is mounted an internally threaded sleeve 27. When the parts are in an operative position, as shown in Figure 4, sleeve 27 is screwed upwardly until it strikes the annular shoulder 25; while the end of the rod 5 is engaging or almost engaging the restricted portion 24. To remove the rod 5 in this form of the invention it would be necessary to rotate the sleeve 27 until it moves downwardly past the restricted portion 24. The rod 5 may then be swung to one side and lifted out of the socket 6. It will be noted that the flange 20 is connected with the plate 23 by a screw 28 which also acts to connect the keeper to the door jam 2.

In Figures 6 and 7 a further form of the invention is shown wherein the keeper 29 is identical with the keeper 30 of the form shown in Figure 4, but in this form of the invention, the keeper is not connected with any reinforcing plate, as, for instance, plate 23, but is set into the door jam in a desired way and is held in place by the various screws 31. One of the screws 31 also passes through the upstanding flange 32 and thereby holds the bracing fixture 33 in place. This fixture is provided with a body 34 fitting against the lower edge of the keeper 29, said body merging into an enlarged rounded portion 35 having a reduced portion 36, whereby a shoulder 37 is presented similar to the shoulder 35 illustrated in Figure 4. The stay rod 5 may be used in connection with

65.

this form of invention in a similar manner to the way it is used in Figure 4.

I claim:

1. A stay for lock keepers including a reinforcing plate having a depression, means for fastening a lock keeper in said depression, a fitting having a notched formation substantially straddling one corner of said plate, said notched formation merging into a reduced extension and a brace removably connected with said fitting for bracing the same part of said brace slidably fitting over said reduced extension. 75

2. A stay for lock keepers including a fixture having a body fitting the central part of the keeper, and a flange fitting flatwise against the inner surface of the keeper, means extending through the keeper and the fixture for connecting the parts together, a bracing fitting having a notched formation substantially straddling one corner of said keeper and merging into an enlargement having a reduced extension whereby a shoulder is presented and a bracing rod positioned with one end against the reduced extension, said rod having an adjustable sleeve positioned to telescope over part of the rod and over the reduced extension so as to rest against said shoulder. 90

3. The combination with a lock keeper of a plate formed with a flat portion fitting flatwise against the keeper, a notch for receiving one corner of the keeper and a reduced extension acting as an abutment, a stay rod having a threaded upper end and a threaded sleeve threaded on to said threaded upper end, said sleeve being adapted to be screwed outwardly from said stay rod to telescope over said reduced extension for keeping the reduced extension and the stay rod in alignment, said sleeve slidably fitting over said reduced extension. 95 100 105 110
